UNITED STATES PATENT OFFICE.

RALPH SHIPMAN, OF SUNBURY, PENNSYLVANIA.

CARBURETER FOR INTERNAL-COMBUSTION ENGINES.

1,076,244.

Specification of Letters Patent

Patented Oct. 21, 1913.

Application filed July 2, 1910. Serial No. 570,101.

To all whom it may concern:

Be it known that I, RALPH SHIPMAN, a citizen of the United States, residing at Sunbury, in the county of Northumberland and State of Pennsylvania, have invented certain new and useful Improvements in Carbureters for Internal-Combustion Engines, of which the following is a specification.

10 The purpose of this invention is to provide a more efficient carbureter for internal combustion engines than the devices now generally employed for that purpose.

15 The details and advantages of the invention will be pointed out in the following specification taken in connection with the accompanying drawing, in which,—

Figure 1 is a vertical section through a carbureter comprising the carbureting chamber, a fuel reservoir and my improved atomizing devices, the section being taken on the line 1—1 of Fig. 2; Fig. 2 is a section on the line 2—2 of Fig. 1, the atomizer being shown in dotted lines; Fig. 3 is a central vertical section through the atomizer, the latter being shown on an enlarged scale; and Fig. 4 is a section on the line 4—4 of Fig. 3.

Referring to the drawing, A indicates a 20 reservoir for containing liquid fuel, such as gasoline, and in which, in practice, the fuel is maintained at a practically constant level by means of a valve, not shown in the drawing, but well understood in the art.

25 Thus the fuel may be maintained at a level indicated by the dotted line 1 or at any desired point above or below said line, as may seem desirable. Fuel, it will be understood, enters the bottom of the reservoir, through the threaded opening 2 in the bottom of the reservoir and passes upward into the tank through a port 3 in a diaphragm 4, which port is to be controlled by a valve in the reservoir. Upon the side of the reser-

30 voir is secured a bracket 5 upon which is mounted a carbureting chamber B which may be of any suitable type, but which is preferably of the type shown in my prior Patent No. 783,902. The carbureting chamber shown in the drawing, comprises a tubular casing, one end of which is provided with a suitable fitting 6 for connection with the intake port of an internal combustion engine, while the opposite end 7 is open so that air may freely flow into the casing from said latter end. A transverse shaft 8

extends through the upper part of the carbureting chamber near its inlet end and upon this shaft is secured a valve 9 which extends toward the outlet end of the chamber. This valve normally takes an inclined position, as shown, its forward end being provided with a stop 9^a which rests upon the bottom of the chamber and supports the forward end of the valve a short distance 60 above the bottom of the chamber. A wire spring 10 passing through an opening 11 in the bottom of the chamber connects the valve with a stud or post 12 upon the side of the reservoir and holds the valve normally in the position shown in Fig. 2. The draft created by the suction of the engine, however, will lift the valve against the tension of the spring and allow more or less air to pass through the chamber according 65 to the requirement of the engine. A damper 13, consisting of a butterfly valve, is arranged between the valve 9 and the outlet port 6, and the shaft 13^a of this damper, it will be understood, is manually controlled 70 by the operator of the engine to throttle the flow of the mixture, as desired.

A lever 14 on the shaft 8, resting upon the operating arm 13^b raises and lowers the valve 9 mechanically and in proportion to 75 the extent to which the valve 13 is opened or closed, thus allowing the air to flow under the valve 9 with less restriction when the valve 13 is wide open than when the valve 13 approaches its closed position. 80

The features above described are, in the main, found in my earlier patent above referred to. My present invention relates more particularly to the atomizing device and to the combination thereof with a combustion chamber having a draft-controlled valve such as the valve 9. The atomizing device is indicated by the letter C and it comprises inner tubes 15 and 16, respectively, and a device 24 for adjusting the inner tube 95 relatively to the outer tube. The outer tube, 15, is exteriorly threaded and fitted with a head 15^a at its lower end, and the exteriorly threaded portion of the outer tube fits into a threaded opening 18 in the bracket 5. The upper portion of said tube 15 extends 100 through an opening 19 in the bottom wall of the carbureting chamber so that the open end 15^b of the tube communicates with said chamber. A short distance below said open 105 end, the tube 15 is provided with one or more openings 15^c in its wall for admitting

air to the tube. The under side of the wall of the carbureting chamber is recessed, as shown at 20, opposite the ports 15^a, and the recess 20 communicates with the atmosphere through a suitable passageway 21 connecting with the recess 20, the arrangement being such that air may flow into the ports 15^a and thence out of the port 15^b and into the carbureting chamber. The outer tube 15 is also provided with ports or passageway 15^d, adjacent to the head 15^a and the bracket 5 has on its under side a recess 22 communicating through a passageway 23 with the reservoir A. When the atomizer is in position, as shown in Fig. 1, the head 15^a closes the lower side of the recess 22 and the liquid fuel may pass from the reservoir through the passageway 23 into the recess 22 and thence through the ports or passageways 15^d into the interior of the tube 15.

The inner tube 16 is open at both ends and longer than the outer tube. A head 16^a is secured to the lower end of the inner tube and this head fits within a casing 24, the inner wall of which, for a portion of its length, has angular faces 24^a for engaging the sides of the head to turn the same. Between the head 16^a and a shoulder 24^b in said casing is interposed a spring 25. The lower end of the casing 24 is closed, liquid tight, by a suitable head 24^c. The tube 15 is interiorly threaded below the air inlet ports 15^c, and that portion 16^b of the inner tube which fits between the ports 15^c and 15^d of the outer tube is exteriorly threaded to engage the interior threads of the tube 15. Thus there is a close fitting threaded connection between the two tubes at a point between the air inlet ports 15^c and the fuel inlet ports 15^d of the outer tube. Below the threaded portion of the inner tube, said tube is restricted in diameter so as to afford a space 26 between the tubes for the flow of liquid fuel, and the inner tube is provided with a longitudinal slot 16^e to permit the liquid to flow from the space 26 into the interior of said tube. It will be understood that the fuel, standing, in the reservoir, at a level above the passageway 23, will flow by gravity through the ports 15^d and fill the space 26, and the casing 24 and will rise in the inner tube to the level of the fluid in the reservoir. A suitable packing 27 is arranged between the casing 24 and the head 15^a and since the spring 25 constantly tends to force the casing 24 toward the head 15^a, the packing 27 is constantly compressed and a tight joint, which prevents the escape of liquid is maintained. The upper end portion 16^d of the inner tube is restricted in diameter so as to provide an annular air space 28 between the tubes opposite the ports 15^c and extending to the outlet port 15^b of the outer tube. As shown at 16^e the outer wall of the inner tube is

conical at its upper end, and the inner wall of the outer tube also preferably converges as shown at 15^e so that the air flowing in at the ports 15^c will flow out at the port 15^b in the form of a cone the apex of which is above the outlet end of the fuel tube. By turning the cylindrical casing 24 the inner tube may be adjusted within the outer tube so as to vary the distance between the conical ends of the same and thus regulate the flow of air.

The atomizer is located, as shown in dotted lines in Fig. 2, so that the outlet ends of the two tubes will be approximately at the end of the valve 9, and in operation, at each suction stroke of the engine piston, air will be drawn through the carbureting chamber from the open end 7 under the valve 9 and over the open ends of the atomizer tubes, and the draft thus created will cause air to be drawn through the outer tube of the atomizer and the liquid fuel to be drawn through the inner tube of the atomizer into the carbureting chamber. The proportion of fuel to air is varied by the relative positions of the tubes, while the quantity of mixture taken into the engine with any given adjustment varies according to the draft created by the suction of the engine.

My improved carburetor is particularly efficient at low speeds, where the draft created by the engine is less than at high speeds, this efficiency being due to the fact that, with the arrangement described, the proportions of air and liquid fuel, are automatically maintained constant at the different speeds and the liquid is intimately mixed with the air at the outlet orifices of the atomizer.

What I claim is:

1. An atomizer for explosive engines comprising an outer tube having air and fuel inlet ports, an inner tube having a part fitting closely within the outer tube between said ports, and said tubes being separated above and below said part to provide spaces between the tubes, said inner tube projecting beyond the lower end of the outer tube, and a casing having means for engaging and moving the inner tube with respect to the outer tube, said casing closing the lower ends of both tubes and forming a well for the liquid fuel.

2. An atomizer for explosive engines comprising an outer air tube, a fuel tube having a threaded connection with the interior of the air tube, a casing inclosing one end of the inner tube and a spring arranged to press said casing toward the lower end of the outer tube.

3. An atomizer for explosive engines comprising an outer air tube, a fuel tube having a threaded connection with the interior of the air tube, a head upon the fuel tube,

a cylindrical casing inclosing the head and having angular inner walls for engaging the faces of the head, and a spring interposed between said head and a shoulder in 5 the casing.

4. An atomizer for explosive engines comprising an outer air tube, a fuel tube having a threaded connection with the interior of the air tube, a casing inclosing the lower 10 end of the fuel tube and a spring arranged to press said casing toward the lower end of the air tube.

5. An atomizer for explosive engines comprising an outer air tube, a fuel tube having a threaded connection with the interior of the air tube, a casing inclosing the lower 15 end of the fuel tube and adapted to engage and turn the latter, and a spring arranged to press said casing toward the lower end 20 of the air tube.

6. An atomizer for explosive engines comprising an outer tube having an air inlet port near its upper end and a fuel inlet port below said air inlet port, and a fuel tube

having a threaded connection with the interior of the outer tube between said air and fuel inlet ports, said fuel tube having an inlet port communicating with the fuel inlet port of the outer tube, a casing inclosing the lower end of the fuel tube and adapted for 30 engaging and turning said fuel tube and a spring normally pressing said casing toward the lower end of the outer tube.

7. In an atomizer for explosive engines, inner and outer tubes having a threaded 35 connection with one another, each tube having a head at its lower end, a casing inclosing the lower end of the inner tube and having angular faces for engaging the head thereon, and a spring within the casing and 40 normally tending to press the casing toward the head on the outer tube.

In testimony whereof I affix my signature, in presence of two witnesses.

RALPH SHIPMAN.
